FIG. 3

UNITED STATES PATENT OFFICE

2,239,350

SHUTTLE BOX

Horace H. Burdett, Milford, Mass., assignor to
Draper Corporation, Hopedale, Mass., a corpor-
ation of Maine

Application August 7, 1940, Serial No. 351,669

6 Claims. (Cl. 139—183)

This invention pertains to fly shuttle looms, and has more particular reference to shuttle boxes for such looms.

Looms of the type to which my invention applies commonly include a reciprocating lay on which is mounted a shuttle box in which a fly shuttle is received. The shuttle box includes a back box plate having a shuttle guiding surface which must be accurately aligned with the reed so as to properly start the shuttle on its flight across the loom. The outer end of the back box plate is usually rigidly fastened to the lay, either the fastening means or the box plate being constructed to provide for proper adjustment of the shuttle guiding surface; since the inner end of the box plate is fixed with respect to the lay, being usually fixed to the lay sword, the attaching means for the inner end of the box plate must provide or permit the desired adjustment of the box plate.

Accordingly, it is the principal object of the present invention to provide in a loom having a lay, lay sword and back box plate having an adjustable shuttle guiding surface, an adjusting member movable transversely of the sword and lay and having a surface abutting a complementary surface of the box plate, the complementary abutting surfaces being so constructed and arranged as to provide a universal adjustment of the box plate about said member, and means for locking the adjusting member and the box plate in adjusted position.

The foregoing and other objects of the invention are accomplished in the construction illustrated on the accompanying drawing, of which:

Fig. 1 is a plan view of a lay beam, shuttle box and other parts of a loom to which the invention has been applied;

Fig. 2 is a horizontal sectional view of certain parts of Fig. 1, this view being to a larger scale;

Fig. 3 is a sectional view taken on line 3—3 of Fig. 2, and;

Fig. 4 is a sectional view taken on line 4—4 of Fig. 2, this view being to a larger scale.

The drawing shows but part of a loom having my invention applied thereto, the parts and mechanisms not shown being of any suitable usual construction and forming no part of the present invention. The drawing shows the right hand end of the usual lay beam 1 which is fixed to the front face of a sword 2 in the usual manner. A shuttle box is mounted on the lay beam and includes a front box plate 3 and a back box plate the outer end 4 of which is fixed to the lay beam as by means of a bolt 5. The back box plate is

provided with a shuttle guiding surface which must be accurately aligned with the reed 5' as is well known in the art. The particular back box plate shown is constructed of two separate pieces, the outer end or piece 4 being relatively fixed and the inner end or piece 6 which carries the shuttle guiding surface 7 being adjustable. The two pieces may be connected by a universal joint indicated generally at 8 and more fully disclosed in patent to W. I. Stimpson, No. 1,848,674 granted March 8, 1932.

The universal joint permits the shuttle guiding surface to be adjusted about different axes, one extending horizontally longitudinally of the lay and shuttle box and the other extending vertically. In other words, the shuttle guiding surface may be tilted about a horizontal axis to bring it into a plane parallel with the reed, and the inner piece having the shuttle guiding surface 20 may be moved bodily forwardly or rearwardly into horizontal alignment with the reed.

The lay carries a reed 5' and also carries at either end a shuttle box. The shuttle 9 is alternately picked from side to side of the loom by mechanisms such as picker stick 10 carrying the picker 11.

The inner end 6 of the back box plate is fixed to the sword 2 by means which can be manipulated to produce the desired adjustment of the shuttle guiding surface, the back box plate being firmly fixed in position after the adjustment is accomplished. Such adjusting means may comprise a plate 12 fixedly secured to the sword 2 by means of screw bolts 13 and 14 passing through elongated holes 15 and 16 in plate 12 whereby the plate 12 is vertically adjustable on the sword 2.

An adjustable stud 17 is threaded into plate 12 and extends through an opening 18 in the sword 2. Stud 17 is movable transversely of plate 12, sword 2, lay 1 and the reed 5'. The forward end of stud 17 is provided with a head 19 having a concave surface 20. Stud 17 has an axial bore 21 for the reception of a bolt 22 extending therethrough for a purpose later to be described.

The inner end or piece 6 of the back box plate is provided with a projection 23 on its rear face. The projection 23 has a convex surface 24 complementary to the concave surface 20 of the stud 17. These two complementary surfaces, 20 and 24 form a universal joint connecting the inner end of the box plate and the forward end of stud 17. The inner end 6 of the box plate has an opening 25 therein having a concave countersink 26 for the reception of the convex head 27 of the bolt 22. Bolt 22 extends through the opening 25

in the box plate 6 and the axial bore 21 of the adjustable stud 17 and is secured therein by means of washers 27 and nut 28. The adjustable stud 17 is provided with radial slots 29 adjacent one end for reception of means for turning the stud. Stud 17 also is provided with a slot 30 extending transversely substantially half way through the stud. Upon tightening the nut 28 on bolt 22, the stud 17 is compressed and due to the weakness of that part of stud 17 in which slot 30 is located, the threads of the stud 17 will be more tightly pressed against the threads of the member 12, thereby preventing turning of the stud 17 in the member 12 and locking the stud in member 12.

Thus it is seen that I have provided means whereby the shuttle guiding surface 1 of the inner end of the box plate 6 may be readily and easily aligned with the reed. Due to the co-operation of the complementary curved surfaces 20 and 24 of the box plate 6 and stud 17 respectively, the box plate is adjustable in relation to the reed about a horizontal axis extending longitudinally of the lay. Due to the transverse movement of the stud 17 the box plate 6 is moved forwardly or rearwardly into horizontal alignment with the reed. After the proper adjustment has been made, the box plate may be locked in adjusted position by means of the bolt 22 and nut 28. Further, as nut 28 is tightened on bolt 22 the stud 17 is locked against movement by compression of the slot 30. In addition to the foregoing adjustments, the entire assembly may be adjusted in a vertical plane in relation to the sword by means of the slot and bolt connections of member 12 with the sword 2.

Having fully disclosed the preferred embodiment of my invention, I claim:

1. In a loom, the combination of a lay, a lay sword for supporting said lay, said sword having an opening therein, a shuttle box carried by said lay, said shuttle box including a back box plate having a shuttle guiding surface, means securing the outer end of said box plate to said lay, a member vertically adjustably connected to said sword and extending through said opening for movement transversely of said sword, the inner end of said box plate and said member having complementary curved contacting surfaces whereby said box plate is adjustable in relation to said member and means for locking said box plate and said member in adjusted position.

2. In a loom, the combination of a lay, a sword for supporting said lay, a member adjustably connected to said sword for movement longitudinally and transversely thereof; a shuttle box carried by said lay, said shuttle box including a back box plate having a shuttle guiding surface, means securing the outer end of said box plate to said lay, the inner end of said box plate and said member having abutting surfaces so constructed and arranged as to form a universal joint whereby said box plate is universally adjustable about said

member and means for locking said box plate and said member in adjusted position.

3. In a loom, the combination of a lay adapted to carry a reed, a lay sword, and a shuttle box carried on said lay, said shuttle box including a back box plate comprised of an outer member pivotally secured at its outer end to the lay and an inner member provided with a shuttle guiding surface, said members being connected by a universal joint, and means for adjustably securing the inner end of said inner member to the lay sword, said means including an adjustable member carried by said sword and movable transversely thereof, said adjustable member and said inner end of said inner member being connected by a universal joint whereby said inner member may be adjusted in relation to said adjustable member about a horizontal axis, and means for locking said inner member and said adjustable member in adjusted position.

4. In a loom, the combination of a lay adapted to carry a reed, a lay sword, a shuttle box including a back box plate having a shuttle guiding surface, means securing the outer end of said box plate to said lay, a member adjustably connected to said sword and movable transversely thereof, the inner end of said box plate and said member having complementary surfaces forming a universal joint whereby said box plate is adjustable in relation to said member, and means for locking said box plate and said member in adjusted position.

5. In a loom, the combination of a lay adapted to carry a reed, a sword for supporting said lay, a shuttle box carried by said lay and having a back box plate including an inner end adapted to be aligned with said reed, a member adjustably connected to said sword and movable transversely thereof, said member and said inner end of said box plate having complementary abutting surfaces so constructed and arranged as to provide universal adjustment of said box plate about said member, and means for locking said box plate and said member in adjusted position.

6. In a loom, the combination of a lay, a sword for supporting said lay, said sword having an opening therein, a member connected to said sword and vertically adjustable thereon, an adjustable stud carried by said member and extending through said opening and movable transversely of said sword, said stud having a concave surface at one end, a shuttle box carried by said lay, said shuttle box including a back box plate having a shuttle guiding surface, means securing the outer end of said box plate to said lay, the inner end of said box plate having a convex surface abutting said concave surface of said stud whereby said box plate is adjustable in relation to said stud about a horizontal axis, and a bolt extending through said box plate and said stud for securing said box plate and said stud in adjusted position.

HORACE H. BURDETT.
